FIG. 4.

PHILIP HEFFLER
INVENTOR

BY *Victor J. Evans,*
ATTORNEY

UNITED STATES PATENT OFFICE.

PHILIP HEFFLER, OF PITTSBURGH, PENNSYLVANIA, ASSIGNOR OF ONE-HALF TO
HARRY C. SIMMONS, OF CRAFTON, PENNSYLVANIA.

OIL STILL.

Application filed January 29, 1924. Serial No. 689,314.

To all whom it may concern:

Be it known that I, PHILIP HEFFLER, a citizen of the United States, residing at Pittsburgh, in the county of Allegheny and State of Pennsylvania, have invented new and useful Improvements in Oil Stills, of which the following is a specification.

This invention relates to oil stills and more particularly to a still of the regenerative type in which checkers are used.

This invention is intended more particularly as an improvement over the still disclosed in my U. S. Patent 1,463,698 dated July 31, 1923, and one of the main objects of the present invention is to provide a still in which the tank or container will be uniformly heated throughout its entire length. A further object is to provide means for admitting air to the checkers, this means being so disposed and arranged that the heat retained by the structure of the casing and the heat generated in the checkers will heat the air admission means to a high temperature so that the air which enters the checkers is preheated. A further object is to provide a still of the character stated of simple construction and operation which may be constructed at comparatively low cost. Further objects will appear from the detail description.

In the drawings:

Figure 1 is a central longitudinal vertical section through the still, parts being shown in elevation;

Figure 2 is a section taken substantially on line 2—2 of Fig. 1;

Figure 3 is a section taken substantially on line 3—3 of Fig. 1;

Figure 4 is a section taken substantially on line 4—4 of Fig. 1.

The still includes a suitable casing 1 of rectangular form, this casing and the parts which are exposed to the action of heat being constructed of any suitable or preferred refractory material. Casing 1 is divided into two compartments by means of a center wall 2 which extends longitudinally of the casing, this center wall extending from the bottom 1^a of the casing to a tank or container 3 which is supported in the upper portion of the casing. A bridge wall 4 extends from each side of center wall 2 to side walls 1^b of the casing, this bridge wall forming with the center wall 5 and the side walls 1^b and front wall 1^c two

fire boxes or combustion chambers 5 which are positioned at opposite sides of the center wall at the front of the furnace. Front wall 1^c is provided with suitable openings 1^d for placing fuel in the combustion chambers or fire boxes when coal or like fuel is used, suitable doors being provided to close these openings, as will be understood. If preferred, however, oil or gas burners or any other suitable heat generating means may be positioned within the combustion chambers 5. An ash pit 6 is formed beneath fire box 5, a suitable grate 7 being supported at the bottom of the fire box, and suitable openings 6^a being provided for cleaning out the ash pits, it being understood that doors of any suitable or preferred type can be provided for closing these openings. A cross wall 8 extends from each face of side wall 2 a short distance in rear of bridge wall 4 and forms therewith a trough or pocket 9 for reception of cinders, ashes and other foreign materials which might tend to clog the checkers, it being understood that one of these troughs is provided at each side of the center wall. In rear of trough 9 there is provided a checker 10 of a known construction supported by crossed walls or sills 11 which may be constructed of tile in a known manner, or of any other suitable or preferred construction. Checker 10 is covered by a covering or floor 12 and the checker terminates a short distance from back wall 1^c of the casing to leave a vertical space or "downcomer" 13 which communicates at its lower end with a flue 14 extending from the back wall of the casing. A clean-out opening 1^e is provided through the back wall so as to facilitate cleaning out of the checker, it being understood that a suitable door is provided for normally closing this opening. As will be noted more clearly from Figures 1 and 4, center wall 2 above the checker coverings or floors 12, terminates a short distance from rear wall 1^c of casing 1 leaving a passover opening 15 which establishes direct communication between the two spaces at the opposite sides of center wall 2. Dampers 16 are slidably mounted in flues 14 for opening and closing the same so as to control the direction of flow of air and products of combustion through the casing, these dampers being operated by means of cables 17 secured thereto and passed over suitable guide pul-

leys 18, counter weights 19 being secured to the other ends of these cables to facilitate adjusting the dampers. Any other suitable or preferred means may be employed, however, for closing and opening the flues 14.

Bridge wall 4 is of hollow construction to provide, at each side of center wall 2, a flue cavity 20, these cavities extending in opposite directions from the center wall and 10 along the side walls 1^b to rear wall 1^c of the casing. An air inlet pipe 21 extends from each side wall of the casing beneath the adjacent checker and through center wall 2, this pipe communicating at its outer end 15 with flue cavity 20 and having its inner end positioned beneath the other checker. Air inlet pipes 22 communicate with the portions of flue cavities 20 in bridge wall 4 and have their outlet ends positioned below and in 20 rear of the checkers positioned at the opposite sides of the center wall 2 from the flue cavities 20 with which the respective pipes communicate. Pipes 23 similar to pipes 22 communicate with the flue cavities in bridge 25 wall 4 and are extended through center wall 2, the outlet ends of these pipes being positioned beneath and substantially centrally of the checkers at the opposite sides of the center wall to the flue cavities with which these 30 pipes communicate. Air ducts 24 extend into center wall 2 from the front wall 1^c of casing 1, these ducts being disposed in superposed relation and communicating with the respective flue cavities 20 of bridge 35 wall 4. Admission of air to the ducts 24 is controlled by valves 25 slidably mounted in guides 26 at the front of the casing. By sliding the upper valve 25 into position to uncover the front end of the upper duct 24, as 40 illustrated in Figure 2, air is admitted to this duct, and is cut off from the lower duct. By reversing the positions of the valves air will be admitted to the lower duct and cut off from the upper duct, as will be 45 understood.

In using the still fires are built in both of the fire boxes 5. With the damper 16 in the lower flue 14, as considered in Figures 2 and 3, closed and the damper in the other 50 flue open, the products of combustion from the upper fire box or combustion chamber 5, as considered in Figures 2 and 3, will flow over bridge wall 4 and across space 9^a between the bridge wall and the checker 10, these products then flowing directly through 55 the checker into the space 13 and thence through flue 14 and into a stack with which the flues communicate. The products of combustion from the other combustion chamber 5 will flow over bridge wall 4 and across space 9^a, these products then flowing 60 through the space between container 3 and floor 12 of the other checker and passing through opening 15, after which the direction of flow of these products is reversed so

that they flow toward the front of the casing in the space between the checker at the upper side of center wall 2 and commingle with the products of combustion from the upper combustion chamber flowing therewith through the first mentioned checker. With the dampers in the positions above stated, and valves 25 in the positions previously referred to, air is admitted to the upper air duct 24. This air flows into the upper flue cavity 20 as considered in Figures 2 and 3 and is drawn through pipes 21, 22 and 23 into the space beneath the lower checker, this air flowing through the checker and commingling with the products of combustion from the lower combustion chamber, this mixture of products flowing through the casing in the manner previously described. By reversing the positions of dampers 16 and of valves 25 the direction of flow of air and products of combustion through the casing may be reversed. In practice the positions of the valve and dampers are reversed approximately every three hours. As will be understood, the checkers, as well as the bridge wall and side walls of the casing, and the air inlet pipes, are all heated to a high temperature so that the air which is drawn through the flue cavities and air ducts and inlet pipes is pre-heated thus facilitating combustion and also eliminating drop in temperature which would result from admitting cold air to the checkers. By employing preheated air the heat retained by the checkers is not as quickly exhausted as if cold air were employed so that I thus obtain a maximum heating effect while also causing the heated air which flows through the checkers and the products of combustion to follow a tortuous path of travel of relatively great length thus obtaining uniform heating of the container 3 and extracting the greater part of heat from the air and products of combustion before they enter the flue, thus producing a still of very high efficiency.

Supplemental air supply pipes 27 and 28 extend through the front wall of the casing, and each of these pipes is provided in its outer portion with a valve 29 of any suitable or preferred type. Pipes 28 extend above the combustion chambers 5 to bridge walls 4, so that the air from these pipes will mix with the products from the combustion chambers to obtain more complete combustion. The pipes 27 extend along the tops of the checkers and have their inner end portions bent at right angles to provide arms 27^a which extend through the cross-over opening 15 so that the outlet of each pipe is at the opposite side of center wall 2 to its inlet. When the lower valve 16, as considered in Fig. 4, is closed valve 29 of the upper pipe 27 is opened, the valve of the lower pipe being closed, and vice versa.

This provides simple and efficient means for providing a supplemental supply of pre-heated air, when desired or necessary, to obtain complete combustion and maximum efficiency. As will be understood, the pipes 27 and 28, as well as all metal parts which are subjected to the direct action of very high temperatures, are covered with asbestos or other suitable or preferred protecting and 10 heat insulating material.

While I have described and illustrated my invention as used in connection with an oil still, it can also be advantageously used in connection with steam generating plants, as 15 will be understood, due to its high efficiency and uniform distribution of heat. Though my invention is more particularly adapted for use in connection with an oil still, I do 20 not desire to be limited to this one particular use.

What I claim is:—

1. In combination with a casing, a container supported in the upper portion of the casing, checkers in the casing beneath the 25 container and spaced therefrom, heating means at one end of the casing, means for admitting air to the checkers, means for causing the products from said heating means to flow through either checker optionally thereby inducing air through the other checker, and means for causing the induced products to flow through the space above said other checker toward one end of the casing and then over the first checker toward 30 the other end of the casing, the induced products commingling with the products of the heating means and flowing therewith through said first checker.

2. In combination with a casing, a container supported in the upper portion of the casing, a center wall dividing the casing into two separate compartments, checkers at one end of the casing at opposite sides of the center wall, combustion chambers at the 45 other end of the casing at opposite sides of said center wall, the center wall terminating above the checkers a short distance from the end wall of said casing, flues communicating with said checkers, and means for closing either flue, optionally, and opening the other flue.

3. In combination with a casing, a container supported in the upper portion of the casing, checkers in the casing beneath the 55 container, heating means at one end of the casing, means for admitting air to the checkers, means for causing the products from said heating means to flow through either checker optionally thereby inducing air through the other checker, and means for causing the induced products to flow through the space above said other checker toward one end of the casing and then over the first checker toward the other end of the casing, the induced products commingling with the 60

products of the heating means and flowing therewith through said first checker, the air admitting means being disposed to be heated by the heat retained by the casing structure and generated in the checkers so as to pre- 70 heat the air admitted to the checkers.

4. In combination with a casing, a container supported in the upper portion of the casing, a center wall dividing the casing into two separate compartments, checkers at one end of the casing at opposite sides of the center wall, bridge walls extending from the opposite sides of the center wall to the side walls of the casing, said bridge walls being of hollow construction to provide flue cavities and the side walls of the casing being provided with flue cavities communicating with the flue cavities of the respective bridge walls, the bridge walls forming with the other end wall and the side walls of the casing combustion chambers, the casing being provided with air inlet ducts communicating with the cavities of the respective bridge walls, flues communicating with the respective checkers, means for closing either flue optionally and opening the other flue, the center wall above the checkers terminating short of the adjacent end wall of the casing, and means for admitting air from the flue cavities at either side of the center wall to the checkers at the other side of said wall. 90

5. In combination with a casing, a container supported in the upper portion of the casing, a center wall dividing the casing into two separate compartments, checkers at one end of the casing at opposite sides of the center wall, bridge walls extending from the opposite sides of the center wall to the side walls of the casing, said bridge walls being of hollow construction to provide flue cavities and the side walls of the casing being provided with flue cavities communicating with the flue cavities of the respective bridge walls, the bridge walls forming with the other end wall and the side walls of the casing combustion chambers, the center wall being provided with air inlet ducts communicating with the cavities of the respective bridge walls, flues communicating with the respective checkers, means for closing either flue optionally and opening the other flue, the center wall above the checkers terminating short of the adjacent end wall of the casing, and means for admitting air from the flue cavities at either side of the center wall to the checkers at the other side of said wall. 110

6. In combination with a casing, a container supported in the upper portion of the casing, a center wall dividing the casing into two separate compartments, checkers at one end of the casing at opposite sides of the center wall, bridge walls extending from the opposite sides of the center wall to the side 125

walls of the casing, said bridge walls being of hollow construction to provide flue cavities and the side walls of the casing being provided with flue cavities communicating with the bridge wall cavities of the respective bridge walls, the bridge walls forming with the other end wall and the side walls of the casing combustion chambers, the casing being provided with air inlet ducts communicating with the cavities of the respective bridge walls, flues communicating with the respective checkers, means for closing either flue optionally and opening the other flue, the center wall above the checkers terminating short of the adjacent end wall of the casing, and air conductors communicating with said flue cavities at opposite sides of the center walls, the conductors which communicate with the flue cavities at one side of said wall discharging into the checker space at the opposite side of the center wall.

7. In combination with a casing, a container supported in the upper portion of the casing, a center wall dividing the casing into two separate compartments, checkers spaced away from one end of the casing at opposite sides of the center wall, the center wall above the checkers terminating a short distance away from the end wall of the casing, bridge walls extending from the opposite sides of the center wall to the side walls of the casing and spaced away from the inner ends of the checkers, said bridge walls being of hollow

construction to provide flue cavities, the side walls of the casing being provided with flue cavities communicating with the bridge wall cavities, means for admitting air to either of the bridge wall cavities optionally, conductors communicating with the flue cavities, the conductors at each side of the center wall passing through the checker space at that side of said wall and discharging into the checker space at the opposite side of the center wall, flues communicating with the spaces between the checkers and the adjacent end wall of the casing, and means for closing either of said flues optionally and opening the other flue.

8. In combination with a casing, a container supported in the upper portion of the casing, two checkers at one end of the casing, two combustion chambers at the other end of the casing, means for admitting air to the checkers, and means for causing the products of combustion from either combustion chamber to flow directly into and through the adjacent checker and for causing the products of combustion from the other chamber together with the air from the other checker to flow through the casing in one direction and then reverse its direction of flow and flow into and through the checker which receives directly the products from its adjacent combustion chamber.

In testimony whereof I affix my signature.
PHILIP HEFFLER.
